PROCESS OF ABSORBING ETHYLENE IN
SULFURIC ACIDJohn S. Atwood, Port Washington, N. Y., assignor
to National Petro-Chemicals Corporation, a
corporation of Delaware

Application May 29, 1952, Serial No. 290,773

10 Claims. (Cl. 260—460)

1 This invention is a new and useful process of absorbing ethylene in sulfuric acid to produce a mixture of mono and diethyl sulfates. The invention is applicable to those mixtures of inert gases and ethylene which are substantially free from higher olefins. The preferred raw material contains from 80 to 98% of ethylene although the process can be used with a gas containing as low as 30% by weight of ethylene. Such gases may be commercially produced by the cracking of natural gas followed by a rectification operation to separate a close cut consisting principally of C-2's. It is preferable but not essential to rectify this mixture further to separate a close cut consisting principally of ethylene.

The invention will be fully understood from the following description read in conjunction with the drawing which is a diagrammatic showing of apparatus in which the invention may be carried out.

Referring to the drawing, a gas stream which has been compressed to a pressure of at least 300 lbs. gauge and from which light fractions such as hydrogen and methane have been removed, is passed through pipe 1 controlled by valve 2 into the mid-section of a rectifying column diagrammatically indicated as 3. This column may be equipped with a reflux device (not shown) adjacent the upper end thereof and with a reboiler (not shown) adjacent the lower end thereof. Rectifying column 3 produces an overhead, consisting principally of C-2's, which is withdrawn through pipe 4, passing thence through control valve 5 into pipe 6 controlled by valves 7 and 8. Bottoms consisting of C-3's and higher is withdrawn through pipe 11 controlled by valve 12 for recracking or utilization elsewhere. This overhead consisting principally of C-2's and containing at least 30% by weight of ethylene may be passed directly through pipes 6 and 20 into the absorbers to be hereinafter described but is preferably passed at least in part through pipe 13 controlled by valve 14 into the mid-section of a second rectifying column diagrammatically indicated as 15.

Column 15 is also equipped with a reflux device (not shown) adjacent the upper end thereof and a reboiler (not shown) adjacent the lower end thereof. This column is adapted and operated to produce an overhead consisting principally of ethylene. Preferably this overhead contains from 80-98% of ethylene, remainder principally ethane. Bottoms from column 15 consisting principally of ethane with some residual gas in which the relative proportion of

5 ethylene is withdrawn through pipe 16 controlled by valve 17 for recracking or utilization elsewhere. The overhead referred to is withdrawn through pipe 18 controlled by pressure reduction valve 19, from which it is discharged into pipe 20 controlled by valves 21 and 22, by which pipe it is discharged into the lower end of the vapor countercurrent contacting device 23, which in the specific case is an absorption tower. This 10 may be of the rectification tower type consisting of a vertical column spanned by horizontal trays equipped with bell caps and downflow pipes, or a packed tower or a sieve tray tower. In either case, it is equipped for the downflow of liquid and for the upflow of gas in countercurrent and intimate contact therewith. Sulfuric acid is introduced into the upper end of 23 through pipe 24 controlled by valve 25. As initially supplied through pipe 24 this sulfuric acid contains from 0.8 to 1.2 mols of ethylene per mol of sulfuric acid and is preferably at a temperature between 160 and 200° F. It flows downwardly within the device 23 in countercurrent contact with the ascending ethylene containing gas and is withdrawn from the base of 23 through pipe 26 controlled by valve 27 into tank 28. Any gas which may be evolved from the absorbate in 28 may be vented through pipe 31 controlled by valve 32. The absorbate may be withdrawn from 28 through pipe 33 controlled by valve 34 for use in the usual way to generate ethyl alcohol or ethyl ether. A number of cooling coils diagrammatically indicated by 35 and 36 are provided upon the trays of 23 or at various liquid levels and these are preferably operated to maintain the temperature of the acid descending through the tower within $\pm 10^{\circ}$ F. of the temperature at which it is introduced through pipe 24.

40 The amount of ethylene introduced through pipe 20 is stoichiometrically at least twice the amount which is absorbed within 23. Although the acid withdrawn from pipe 26 is not fully saturated, containing a maximum of 1.5 mols ethylene per mol of sulfuric acid, the rate of absorption falls off rapidly as this concentration is approached, making it of advantage to feed a substantial excess of ethylene upwardly through 23 while withdrawing an absorbate of this concentration from the base of 23. The use of a large excess of ethylene at this point favors the rapid reaction of ethylene with the acid up to a saturation approaching 1.5 mols of ethylene per mol of sulfuric acid, thereby resulting in efficient utilization of the absorption equipment. The 45 50 55 residual gas in which the relative proportion of

inert diluent is approximately twice that of the feed through pipe 28 is withdrawn through pipe 37 controlled by pressure reduction valve 38. If the feed through pipe 28 is at a pressure of approximately 125 lbs. gauge, in order to maintain favorable absorption conditions in 23, the pressure reduction valve 38 will be set to maintain a back pressure of about 75 lbs. gauge, thereby resulting in the maintenance of an average pressure of approximately 100 lbs. gauge within 23. This is about the lowest limit in which I desire to operate. Preferably, the gas introduced through pipe 28 is at a pressure of at least 225 lbs. gauge, thereby resulting in the maintenance of an average pressure within 23 of at least 200 lbs. gauge.

The overhead passing through pipe 37 and reduction valve 38 moves through pipe 39 into compressor, diagrammatically indicated by 41, by which it is brought to a still higher pressure and delivered through pipe 42 controlled by valve 43 and through pipe 44 controlled by valve 45 into the base of liquid vapor countercurrent contacting device 46. This is similar to 23 in that it is constructed for the downward movement of a liquid countercurrent to an ascending stream of gas and, for this purpose, is equipped with horizontal trays spanning the tower, which trays carry bell caps and downflow pipes. A packed column or a sieve tray column may be similarly employed. Concentrated sulfuric acid may be introduced to the upper end of 46 through pipe 47 controlled by valve 48 and pipe 49 controlled by valve 50. The concentrated sulfuric acid is preferably introduced through pipe 47 at a strength of 96 to 100% H_2SO_4 . As withdrawn from the base of 46 through pipe 51 controlled by valve 52, this acid will contain from 0.8 to 1.2 mols of ethylene per mol of sulfuric acid. Preferably the temperature of the acid moving downwardly within 46 is permitted to rise progressively to 160 to 200° F. and preferably 170 to 190° F. at the base. The acid, containing 0.8 to 1.2 mols of ethylene per mol of sulfuric acid, is withdrawn through pipe 51 controlled by valve 52 and a portion is transferred directly to 23 through pipe 53 and pressure reduction valve 54 into pipe 24. The remainder is passed through cooler diagrammatically indicated by 55, by which it is reduced in temperature and thence moves from cooler 55 to pipe 56 controlled by valve 57 into pump 58, by which it is recirculated through pipe 59 controlled by valve 61 into the contacting device 46. The amount of acid recycled in this way through pump 58 may range from 2 to 10 times by weight the amount of the fresh acid introduced through pipe 47. The temperature of the combined streams of acid entering the top of tower 46 may range between 100 and 180° F.

Residual gas consisting principally of ethane is withdrawn from 46 through pipe 62 controlled by pressure reduction valve 63. The pressure drop in 46 may be approximately 50 lbs., resulting in the maintenance of an average pressure approximately 25 lbs. less than that for which reduction valve 63 is set. In this way the average pressure obtaining in 46 will be adjusted to at least 50% higher than the average pressure obtaining in 23 and preferably at least 100% higher. This results in optimum reaction conditions with a through-put that is extremely high for any particular equipment. In practice, the gas passing through pressure reduction valve 63 into pipe 64 will ordinarily be recycled into the feed to tower 3.

I find it of further advantage to combine with the gas introduced to the base of 46 through pipe 44 part of the overhead from rectifying column 3. This cut consists almost entirely of C-2's although it does not have the ethylene concentration of the overhead from column 15. However, by conducting part of the overhead consisting predominantly of C-2's from rectifying column 3 through pipe 6 controlled by valves 7 and 8, and combining this with the compressed gas in pipe 42, I am able to absorb considerably more ethylene in 46 than would otherwise be the case, and since the gas in line 6 is already at a pressure at least equal to that obtaining in 42 and at 15 a concentration of ethylene in the range of that obtaining in line 42, it is not necessary to re-compress the gas in pipe 6 nor is it necessary to rectify further that portion of the overhead from rectifying column 3 to increase the concentration of ethylene therein.

The amount of gas introduced to 46 through pipe 6 is preferably sufficient to convey an amount of ethylene ranging from one-half to twice the amount absorbed in 23. As a result of 25 this procedure the amount and rate of absorption in tower 46 is comparable to that obtaining in 23. The decreased partial pressure of the ethylene is compensated for by the absolute amount present, the increased total pressure, and 30 the higher concentration of the sulfuric acid at this stage.

The foregoing description is for purposes of illustration and not of limitation and it is, therefore, my intention that the invention be limited 35 only by the appended claims or their equivalents wherein I have endeavored to claim broadly all inherent novelty.

I claim:

1. Process of absorbing ethylene in sulfuric acid to form a mixture of monoethyl and diethyl sulfates, which comprises maintaining a first liquid-vapor counter-current contacting device under an average pressure of at least 100 lbs. p. s. i. g., maintaining a second liquid-vapor countercurrent contacting device under an average pressure at least 50% greater than that obtaining in said first device, with series connections between said first and second devices for the transfer of vapor with intermediate compression from the upper end of said first device into the lower end of said second device, and for the transfer of acid from the lower end of said second device into the upper end of said first device, introducing sulfuric acid containing from 0.8-1.2 mols ethylene per mol H_2SO_4 into the upper end of said first device, conducting away from the lower end of said first device sulfuric acid containing from 1.3-1.5 mols ethylene per mol H_2SO_4 , introducing a gas, the olefine content of 55 which consists substantially exclusively of ethylene containing at least 30% by weight of ethylene and containing inert diluents, into the lower end of said first device, the amount of ethylene present in said gas being at least twice the amount which is absorbed in said first device, conducting residual gas containing ethylene and inert diluents from the top of said first device, compressing same and introducing the compressed gas into the lower end of said second device, introducing concentrated sulfuric acid into the upper end of said second device, conducting away from the base of said second device sulfuric acid containing from 0.8-1.2 mols ethylene per mol of sulfuric acid and introducing at least a 70 75 part of the same into the top of said first device.

2. Process according to claim 1 in which the average pressure obtaining in said second device is at least 100% greater than the average pressure obtaining in said first device.

3. Process of absorbing ethylene in sulfuric acid to form a mixture of monoethyl and diethyl sulfates, which comprises maintaining a first liquid-vapor countercurrent contacting device under an average pressure of at least 200 lbs. p. s. i. g., maintaining a second liquid-vapor countercurrent contacting device under an average pressure at least 50% greater than that obtaining in said first device, with series connections between said first and second devices for the transfer of vapor with intermediate compression from the upper end of said first device into the lower end of said second device and for the transfer of acid from the lower end of said second device into the upper end of said first device, introducing sulfuric acid containing from 0.8-1.2 mols ethylene per mol H_2SO_4 into the upper end of said first device, conducting away from the lower end of said first device sulfuric acid containing from 1.3-1.5 mols ethylene per mol H_2SO_4 , introducing a gas, the olefine content of which consists substantially exclusively of ethylene containing at least 30% by weight of ethylene and containing inert diluents, into the lower end of said first device, the amount of ethylene present in said gas being at least twice the amount which is absorbed in said first device, conducting residual gas containing ethylene and inert diluents from the upper end of said first device, compressing same and introducing the compressed gas into the lower end of said second device, introducing concentrated sulfuric acid into the upper end of said second device, conducting away from the base of said second device sulfuric acid containing from 0.8-1.2 mols ethylene per mol of sulfuric acid and introducing at least a part of the same into the top of said first device.

4. Process according to claim 3 in which the average pressure obtaining in said second device is at least 100% greater than the average pressure obtaining in said first device.

5. Process of absorbing ethylene in sulfuric acid to form a mixture of monoethyl and diethyl sulfates, which comprises maintaining a first liquid-vapor countercurrent contacting device under an average pressure of at least 100 lbs. p. s. i. g., maintaining a second liquid-vapor countercurrent contacting device under an average pressure at least 50% greater than that obtaining in said first device, with series connections between said first and second devices for the transfer of vapor with intermediate compression from the upper end of said first device into the lower end of said second device and for the transfer of acid from the lower end of said second device into the upper end of said first device, introducing sulfuric acid containing from 0.8-1.2 mols ethylene per mol H_2SO_4 into the upper end of said first device, conducting away from the lower end of said first device sulfuric acid containing from 1.3-1.5 mols ethylene per mol H_2SO_4 , introducing a gas containing at least 30% by weight of ethylene and containing inert diluents, into the lower end of said first device, the amount of ethylene present in said gas being at least twice the amount which is absorbed in said first device, conducting residual gas containing ethylene and inert diluents from the upper end of said first device, compressing same and introducing the compressed gas into the

lower end of said second device, introducing concentrated sulfuric acid into the upper end of said second device, conducting away from the lower end of said second device sulfuric acid containing from 0.8-1.2 mols ethylene per mol of sulfuric acid, discharging a part of said last mentioned sulfuric acid into the upper end of said first device and combining the remainder with the concentrated sulfuric acid introduced into the upper end of said second device.

6. Process according to claim 5 in which the average pressure obtaining in said second device is at least 100% greater than the average pressure obtaining in said first device.

7. Process of absorbing ethylene in sulfuric acid to form a mixture of monoethyl and diethyl sulfates, which comprises maintaining a first liquid-vapor countercurrent contacting device under an average pressure of at least 100 lbs. p. s. i. g., maintaining a second liquid-vapor countercurrent contacting device under an average pressure at least 50% greater than that obtaining in said first device, with series connections between said first and second devices for the transfer of vapor with intermediate compression from the top of said first device into the lower end of said second device and for the transfer of liquid from the lower end of said second device into the upper end of said first device, introducing sulfuric acid containing from 0.8-1.2 mols ethylene per mol H_2SO_4 at a predetermined temperature between 160 and 200° F. into the top of said first device, abstracting heat from said sulfuric acid as it descends within said first device at a rate sufficient to maintain said predetermined temperature within ± 10 ° F., conducting away from the lower end of said first device sulfuric acid containing from 1.3-1.5 mols ethylene per mol H_2SO_4 , introducing a gas, the olefine content of which consists substantially exclusively of ethylene containing at least 30% by weight of ethylene and containing inert diluents, into the lower end of said first device, the amount of ethylene present in said gas being at least twice the amount which is absorbed in said first device, conducting residual gas containing ethylene and inert diluents from the upper end of said first device, compressing same and introducing the compressed gas into the lower end of said second device, introducing concentrated sulfuric acid at a temperature between 100 and 180° F. into the upper end of said second device, permitting the temperature of the descending stream of acid within said second device to rise exothermically to 160-200° F. at the base thereof, conducting away from the base of said second device sulfuric acid containing from 0.8-1.2 mols ethylene per mol of sulfuric acid and introducing at least a part of the same into the upper end of said first device.

8. Process of absorbing ethylene in sulfuric acid to form a mixture of monoethyl and diethyl sulfates, which comprises maintaining a first liquid-vapor countercurrent contacting device under an average pressure of at least 100 lbs. p. s. i. g., maintaining a second liquid-vapor countercurrent contacting device under an average pressure at least 50% greater than that obtaining in said first device, with series connections between said first and second devices for the transfer of vapor with intermediate compression from the upper end of said first device into the lower end of said second device and for the transfer of liquid from the lower end of said second device into the upper end of said first device, introducing sulfuric acid containing from

0.8-1.2 mols ethylene per mol H_2SO_4 at a predetermined temperature between 160 and 200° F. into the upper end of said first device, abstracting heat from said sulfuric acid as it descends within said first device at a rate sufficient to maintain said predetermined temperature within ± 10 ° F., conducting away from the lower end of said first device sulfuric acid containing from 1.3-1.5 mols ethylene per mol H_2SO_4 , introducing a gas, the olefine content of which consists substantially exclusively of ethylene containing at least 30% by weight of ethylene and containing inert diluents, into the lower end of said first device, the amount of ethylene present in said gas being at least twice the amount which is absorbed in said first device, conducting residual gas containing ethylene and inert diluents from the upper end of said first device, compressing same and introducing the compressed gas into the lower end of said second device, introducing concentrated sulfuric acid at a temperature between 100 and 180° F. into the upper end of said second device, permitting the temperature of the descending stream of acid within said second device to rise exothermically to 160-200° F. at the base thereof, conducting away from the base of said second device sulfuric acid containing from 0.8-1.2 mols ethylene per mol of sulfuric acid, discharging a part of said last mentioned sulfuric acid into the upper end of said first device and combining the remainder with the concentrated sulfuric acid introduced into the upper end of said second device.

9. Process of absorbing ethylene in sulfuric acid to form a mixture of monoethyl and diethyl sulfates, which comprises maintaining a first liquid-vapor countercurrent contacting device under an average pressure of at least 100 lbs. p. s. i. g., maintaining a second liquid-vapor countercurrent contacting device under an average pressure at least 50% greater than that obtaining in said first device, with series connections between said first and second devices for the transfer of vapor with intermediate compression from the upper end of said first device into the lower end of said second device, and for

5 the transfer of acid from the lower end of said second device into the upper end of said first device, introducing sulfuric acid containing from 0.8-1.2 mols ethylene per mol H_2SO_4 into the upper end of said first device, rectifying a mixture of C-2 and C-3 hydrocarbons containing olefines to form a first product consisting predominantly of C-2's and containing ethylene, further rectifying this product to form a second product, the olefine content of which consists substantially exclusively of ethylene, containing at least 30% by weight of ethylene and containing inert diluents, introducing such second product into the lower end of said first device, conducting away from the lower end of said first device sulfuric acid containing from 1.3-1.5 mols ethylene per mol H_2SO_4 , the amount of ethylene present in said second product being at least twice the amount which is absorbed in said first device, conducting residual gas containing inert diluents from the upper end of said first device, compressing same to a pressure at least 50% greater than that obtaining in said first device, combining gas so compressed with a part of said first product, introducing the combined gases into the lower end of said second liquid-vapor countercurrent contacting device, introducing concentrated sulfuric acid into the upper end of said second device, conducting away from the base of said second device sulfuric acid containing from 0.8-1.2 mols of ethylene per mol of sulfuric acid and introducing at least a part of the same into the top of said first device.

10. Process according to claim 9 in which the average pressure obtaining in said second device is at least 100% greater than the average pressure obtaining in said first device.
